[57] CLAIM

The ornamental design for a golf club holster, as shown and described.

DESCRIPTION

FIG. 1 is a side elevational view of a golf club holster showing my new design;

FIG. 2 is a rear elevational view of the golf club holster of FIG. 1;

FIG. 3 is a front elevational view of the golf club holster of FIG. 1;

FIG. 4 is a top plan view of the golf club holster of FIG. 1;

FIG. 5 is a bottom plan view of the golf club holster of FIG. 1.

The other side elevational view is a mirror image of the side elevational view of FIG. 1.
